DANIEL HOWE NEILLY, OF BRADFORD, PENNSYLVANIA, ASSIGNOR OF ONE-FOURTH TO W. P. BRINTON, ONE-FOURTH TO J. S. BROWN, AND ONE-FOURTH TO G. W. DOUBLE, ALL OF BRADFORD, PENNSYLVANIA.

CLASP.

Application filed March 25, 1921, Serial No. 455,401. Renewed November 15, 1922. Serial No. 601,166.

To all whom it may concern:

Be it known that I, DANIEL HOWE NEILLY, a citizen of the United States, and a resident of Bradford, in the county of Mc- 5 Kean and State of Pennsylvania, have invented certain new and useful Improvements in Clasps, of which the following is a specification.

The present invention relates to an improvement in clasps, especially adapted for use with rifle straps or the like.

The object of the invention is to provide an improved clasp of this character which is of simple and durable construction, reliable in operation and easy and inexpensive to manufacture, which automatically exerts a powerful gripping or clasping action upon the sections of the rifle strap to maintain them in desired position, 20 which is readily and easily adjustable and is quickly and uniformly effective in any position to which it may be adjusted.

Other objects and advantages of the invention reside in certain novel features of 25 construction, combination and arrangement of parts which will be hereinafter more fully described and particularly pointed out in the appended claims, reference being had to the accompanying drawings forming part 30 of this specification, and in which:

Figure 1 is a view in side elevation, illustrating the clasp in use upon the rifle strap;

Figure 2 is a perspective view of the clasp 35 detached;

Figure 3 is a perspective view of the clasp and rifle strap detached from the rifle, illustrating the cooperation between the clasp and the rifle strap;

40 Figure 4 is a detail view of the coacting plate; and

Figure 5 is a perspective view of a modified form of the invention.

Referring to the drawings wherein for 45 the sake of illustration is shown the preferred embodiment of the invention, the rifle strap is designated at S and may be of any conventional or standard construction and preferably embodies sections s and s' 50 adapted to form at one end a loop l. The loop l encircles the upper arm of the user above or adjacent the upper portion of the

biceps and the other end of the strap is connected to the rifle in the usual manner.

The clasp which is designated generally 55 at C is arranged upon the sections of the strap and has for its function the formation of the loop and the preservation of the loop in the proper position upon the upper arm of the user.

The clasp comprises a frame 10 which includes a plate 11 having one end roughened, as at 12, and constituting a jaw, and side flanges 13 extending at right angles from each side of the plate and preferably formed 65 integral therewith. A pivot pin 14 is provided and has its ends arranged in suitable bearings provided in the side flanges of the frame and thereby constitutes a fulcrum for the plate 11.

A coacting plate 15 having a roughened portion 15^a constituting a jaw is arranged between the side flanges of the frame 10 and is provided with a pair of apertured ears 16 journaled upon the pivot pin 14 whereby 75 the coacting plate is also fulcrumed upon the pivot pin. The pivot pin 14 thus constitutes a fulcrum and it defines on the plate 11 and the coacting plate 15 short lever arms which constitutes the jaws of the clasp 80 and long lever arms which function to operate the jaws in a manner which will hereinafter be more fully described.

Curved lips, designated at 17 and 18, are carried by the plate 11 and the coacting 85 plate 15, respectively, and preferably are formed integral with their respective plates. The curved lips 17 and 18 are controlled by the portions of sections s and s' which constitutes the loop l as when the 90 strap is in use these sections are forced or urged outwardly and throw the jaws into powerful gripping or clasping engagement with the sections of the strap and thus effect the clasping action.

In practice, expert riflemen and sharp shooters find it necessary when shooting from prone position to place a heavy strain upon the rifle strap S. These strains vary with different riflemen and generally ranges 100 from 40 to 150 pounds. In order to do this, the loop of the rifle strap must encircle the upper arm above or adjacent the upper portion of the biceps, must be maintained in

this position and must not be permitted to slide down the arm toward the elbow. The leather keeper and other devices heretofore proposed in the art have not been efficient to 5 maintain the loop in proper position and prevent its sliding down toward the elbow in the manner referred to. With my improved clasp however when the loop is positioned on the arm the loops 17 and 18 10 are pressed inwardly by the fingers of the right-hand of the rifleman and the clasp is slid along the sections of the strap until the loop of the proper size is formed, the loop having of course been properly positioned 15 on the upper arm. Now then, when the strain is placed upon the rifle strap it will spread that portion of the sections *s* and *s'* which constitute the loop *l* and these portions of sections *s* and *s'* act upon the lips 20 17 and 18 to spread them or throw them outwardly away from each other. The lips being formed upon the long arms of the lever throw the short arms which constitute the jaws into powerful gripping engagement 25 with the sections of the strap thus binding the sections together and the clasp to the sections. It is to be noted moreover that the heavier the strain the more powerful the gripping engagement. With the sections of 30 the strap bound together it is impossible for the loop to slide down the arm as it cannot enlarge and will be maintained in proper position.

In Figure 5 there is shown a modified 35 form of the invention especially adapted for use with canvass straps or slings. The canvass straps or slings have hooks riveted to both ends and these prevent the strap being passed through the clasp without taking out the rivets. With these canvass 40 straps a clasp designated at 20, is employed and includes a pair of resilient arms designated at 21, connected to each other by means of a curved resilient spring member 45 22 and terminating at their free ends in hooks or gripping portions 23. In the use of this form of clasp the hooks or gripping portions 23 are utilized to spread the gripping portions of the clasp in order to associate it with the strap and when so associated these hooks are released and the resilient arms allowed to spring into engagement 50 with the strap.

I claim:

55 1. In a device of the character described for use with rifle straps having sections formed at one end in a loop adapted to embrace the arm of the user, a frame including a plate having an end portion constituting a jaw adapted for engagement with a section of the strap and side flanges extending from said plate and embracing the strap, said side flanges being provided with aligned 60 bearings, a pivot pin having its ends re-

ceived in said bearings and constituting a fulcrum for the plate, a coacting plate having a pair of ears provided with aligned apertures journaled upon the pivot pin, said plates having a roughened portion constituting a jaw adapted for engagement with a section of the strap, said pivot pin being arranged with respect to said plate to define in each of said plates a short lever arm and a long lever arm, the short lever arm being the roughened end portions which constitute the jaws, and curved lips carried by the long lever arms of the plates and adapted to be engaged by the sections of the strap which constitute the loop to automatically throw the jaws into powerful gripping engagement 80 with the sections of the strap.

2. In a device of the character described, a frame including a plate having a roughened end portion constituting a jaw, and side flanges extending from said plate and provided with aligned bearings, a pivot pin having its ends arranged in said bearing and constituting a fulcrum for said plate, a coacting plate arranged between the side flanges of said frame and having a roughened end portion constituting a jaw and having a pair of apertured ears fulcrumed upon said pivot pin and curved lips carried by said plates at the ends opposite said jaws.

3. In a device of the character described, a frame including a plate, and side flanges, a pivot pin bearing in said flanges and constituting a fulcrum for said plate, a coacting plate arranged between the side flanges and journaled on said pivot pin, the pivot pin constituting a fulcrum for said plates and defining on said plates a long and a short lever arm, the short lever arm of said plates constituting jaws, and curved lips carried by the long lever arms of said plates.

4. In a device of the character described, coacting plates, a fulcrum therefor defining on each plate a long and a short lever arm, the short lever arms of the plates constituting coacting jaws and curved lips carried by the long lever arms.

5. In a device of the character described, in combination with a rifle strap including sections formed at one end into a loop, a clasp slidably arranged on said sections of the strap and adapted to define a loop and maintain it in proper position, said clasp including coacting plates, a fulcrum therefor defining on each plate, a long and a short lever arm constituting jaws engageable with the strap, and curved lips carried by the long lever arms and operated upon by the portions of the sections of the strap which constitute the loop to throw the jaws of the clasp into powerful gripping engagement with the strap.

6. In a device of the character described, in combination with a rifle strap including

sections, a clasp slidably mounted on the sections of the rifle strap and including coacting plates having portions constituting jaws and curved lips carried by the plates and operated upon by the sections of the strap to throw the jaws into powerful gripping engagement with the strap.

7. In a device of the character described, the combination with a rifle strap, a clasp including jaws engageable with the strap 10 and means under the control of the strap for forcing the jaws into powerful gripping engagement with the strap.

DANIEL HOWE NEILLY.
